(No Model.)

F. CHALLONER.

SPALT DROPPING MECHANISM FOR SHINGLE SAWING MACHINES.

No. 415,857.

Patented Nov. 26, 1889.

UNITED STATES PATENT OFFICE.

FRANK CHALLONER, OF OMRO, WISCONSIN.

SPALT-DROPPING MECHANISM FOR SHINGLE-SAWING MACHINES.

SPECIFICATION forming part of Letters Patent No. 415,857, dated November 26, 1889.

Application filed July 27, 1889. Serial No. 318,970. (No model.)

To all whom it may concern:

Be it known that I, FRANK CHALLONER, of Omro, in the county of Winnebago and State of Wisconsin, have invented certain new and useful Improvements in Spalt - Dropping Mechanism for Shingle-Sawing Machines; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

15 My invention relates to that class of shingle-machines in which a rotary bolt-carriage and a circular track with movable sections for dropping the spalts are employed. Its main object is to facilitate the discharge from 20 the machine of the "spalts" or residuum of the bolts; and it consists, essentially, of mechanism under the control of the operator for effecting that end, hereinafter specifically set forth, and pointed out in the claims.

25 In the accompanying drawings like letters designate the same parts in the several figures.

Figure 1 is a side elevation of the spalt-dropping mechanism in connection with movable sections, and Figs. 2 and 3 are respectively end and side elevations of the clutch for connecting and disconnecting the spalt-dropping mechanism with suitable driving mechanism.

35 Referring to Fig. 1, L L represent movable sections of the curved track upon which the shingle-bolts rest when placed in the carriage.

They are supported at the upper ends of standards l l, which are attached at their 40 lower ends to rock-shafts M M, provided with inwardly-extending arms m m at right angles to said standards.

45 n is a horizontal shaft supported in suitable bearings and extending from the center of the machine outwardly underneath the rock-shafts M M. Upon this shaft is loosely mounted a sleeve O, provided at one end with a cam o, which works at its periphery, with friction-rollers m' on the inner ends of the 50 arms m m, and at the other end with a disk o', the inner face of which is provided on opposite sides of the shaft n with lugs o², one

being shown by full lines in Figs. 1 and 3, and both indicated by dotted lines in Fig. 2.

A similar disk P is keyed upon the shaft n 55 close to the disk o', and is provided on opposite sides of said shaft with two sliding pins p p, parallel with said shaft n and having right-angled projections p' p' at their ends opposite the disk o'. The standards l l are 60 drawn together and the track-sections L L are held in their normal positions by a spring l', attached at its ends to said standards.

A' represents the central vertical shaft of the rotary carriage. It is provided with a 65 bevel-gear A², which engages with and drives a pinion n' on the inner end of the shaft n.

R is a sliding rod supported in suitable bearings parallel with the shaft n, and provided near its inner end with an arc-shaped 70 arm r adjacent to and parallel with the inner face of the disk P in the line of travel of the inner ends of the sliding pins p p. At its outer end said sliding rod R is connected with a foot-lever r', fulcrumed to the frame 75 of the machine. A spiral spring r², placed around said sliding rod R and bearing at one end against one of its fixed supports and at the other against a collar r³, adjustably secured thereon, holds said arm r a short distance from the disk P.

S is a curved wedge-shaped guide supported next to the inner face of the disk P opposite the curved arm r in the line of travel of the projections p' p' on the sliding 85 pins p p, as shown in Figs. 2 and 3. The disks o' and P together constitute a clutch, by means of which the spalt-dropping mechanism is temporarily connected with the driving mechanism. The shaft n has an axial 90 passage extending from one end and opening inside of the sleeve O, and at its outer end communicates with an upwardly-bent tube n², through which oil is supplied to lubricate the bearing of said sleeve. 95

The residuum of each block, called the "spalt," is discharged from the machine, when it passes over the movable sections L L of the track, by the operator depressing the lever r', which moves the arc-shaped arm r towards the disk P and thrusts one of the pins p, which is adjacent to it, toward the disk o' into engagement with one of the lugs o² thereon. The cam o is thus caused to ro- 100

tate in the direction indicated by the arrow in Fig. 2, and one of its elevations, passing under the rollers m' , lifts the arms m m' , throwing the upper ends of the standards l l' and the sections attached thereto outwardly, so as to drop the spalt thereon. As the projecting portion of the cam o leaves said rollers m' , the spring v draws the standards l l' toward each other and returns the track-sections L L' to their normal position. As the pin p in engagement with the lug o^2 passes the inclined guide S in the latter half of its revolution, the projection p' on said pin engages said guide and draws said pin out of engagement with the lug o^2 , thereby arresting the further rotation of said cam when the rollers m' and the track-sections L L' are in the position shown in Figs. 2 and 3. The cam o having two diametrically-opposite projections and the disks o' and P being each provided with two lugs or pins, the proportion of the driving-gear A^2 to the pinion n' is as one-half the number of block-receptacles in the carriage is to one, so that the spalt-dropping mechanism may be operated and a spalt dropped from each block-receptacle in the carriage in succession.

I claim—

1. The combination, in a shingle-machine, with rock-shafts provided with standards to which are attached movable track-sections, and with inwardly-projecting arms, of a cam bearing at its periphery against the inner ends of said arms, driving mechanism, and a clutch arranged to connect and disconnect said cam with said driving mechanism, substantially as and for the purposes set forth.

2. The combination, in a shingle-machine, with a rock-shaft provided with a standard to which is attached a movable track-section, and with an arm at right angles to said standard, of a cam bearing against the free end of said arm, a clutch arranged to connect and disconnect said cam with suitable driving mechanism, and a lever arranged to throw said clutch into and out of gear, substantially as and for the purposes set forth.

3. The combination, in a shingle-machine, with movable track-sections supported upon standards fixed to parallel rock-shafts, and arms projecting inwardly from said rock-

shafts, of a cam bearing against the inner ends of said arms, a clutch consisting of two disks, one fixed to said cam and provided with one or more lugs and the other connected with driving mechanism and provided with one or more sliding pins, a trip arranged to move said sliding pin or pins into engagement with said lug or lugs, and an inclined guide arranged to withdraw said pin or pins out of engagement therewith, substantially as and for the purposes set forth.

4. The combination, in a shingle-machine, with two parallel rock-shafts provided with standards to the upper ends of which are attached movable track-sections, of a spring connecting said standards and arranged to return said track-sections, when released, to their normal position, inwardly-projecting arms fixed to said rock-shafts, a cam having a bearing at its periphery against the inner ends of said arms, a clutch consisting of two disks, one fixed to said cam and the other connected with driving mechanism and provided with two or more laterally-sliding pins which are arranged to engage with the disk fixed to said cam, an arc-shaped arm movable by the operator against the adjacent ends of said pins, and a wedge placed opposite said arm and arranged to withdraw said pins from engagement with the other section of the clutch, substantially as and for the purposes set forth.

5. The combination, in a shingle-machine having a rotary carriage and circular track, of a laterally-movable track-section, a cam operating through suitable mechanism to temporarily remove said track-section from its ordinary position, a clutch arranged to connect said cam with driving mechanism, and a trip under control of the operator arranged to throw said clutch into and out of gear, substantially as and for the purposes set forth.

In testimony that I claim the foregoing as my own I affix my signature in presence of two witnesses.

FRANK CHALLONER.

Witnesses:

E. R. HICKS,
